COMBINATION HAIR CURLING
INSTRUMENT

Dewey E. Harmon, Dallas Center, Iowa

Application October 16, 1933, Serial No. 693,766

6 Claims. (Cl. 132—33)

The principal object of my invention is to provide a compact, easily and quickly operated hair curling instrument that will accommodate any length of hair and provide any desired ratio of 5 croquignole to spiral.

A further object of this invention is to provide a hair curler that makes possible the simultaneous tightening of the spiral and croquignole thereon and will not allow the accidental 10 winding of spiral or croquignole.

A still further object of my invention is to provide a hair curling device that when once a curl of hair is tightened in position on the same, requires no further attention or manipulation to 15 hold the curl or spiral in place.

A still further object of this invention is to provide a combination hair curler that eliminates bulges, humps, and the like between the spiral and croquignole and thereby allows the well 20 known sachet or pad used in setting the curl, to successfully and completely cover and be in proper contact with the hair.

A still further object of this invention is to provide a combination curling device for croquignole and spiral work that is economical in manufacture, durable in use, and efficient in operation. 25

These and other objects will be apparent to those skilled in the art.

My invention consists in the construction, arrangement and combination of the various parts 30 of the device, whereby the objects contemplated are attained as hereinafter more fully set forth, pointed out in my claims and illustrated in the accompanying drawing, in which:

Fig. 1 is an enlarged side view of my device ready for use.

Fig. 2 is an enlarged cross-sectional view of my hair curler taken on line 2—2 of Fig. 1.

Fig. 3 is an enlarged cross-sectional view of the 40 device taken on line 3—3 of Fig. 1.

Fig. 4 is an enlarged side view of a portion of the spiral form with the croquignole form tube broken away, showing the ratchet spring.

Fig. 5 is an enlarged cross-sectional view of the 45 croquignole form, showing the hair-retaining finger.

Fig. 6 is a perspective view of the manually operated hair-retaining clamp.

In the art of curling or permanently waving 50 hair it is generally the practice to wind the hair around a form from the scalp out, in what is known as a spiral curl and then wind the hair from the ends in toward the scalp for a substantial distance to produce what is known as a croquignole curl. Previously, this operation re-

quired separate forms for each style of curl desired or else a separate croquignole form spaced apart from and parallel to the spiral form and rotatably mounted on ears or lugs extending out from the spiral form.

Such cumbersome devices for producing a combination spiral curl and croquignole curl are highly inefficient and objectionable in that a dead or uncurled portion in the hair exists between the spiral curl and the croquignole curl. 10 Furthermore, such devices are objectionable in that they do not eliminate humps or bulges in the wound hair and the treating pads or sachets cannot successfully contact and properly cover the hair to be treated. My device overcomes 15 such disadvantages, besides being capable of accommodating various lengths of hair and curling the hair successfully and tightly adjacent the scalp.

Referring to the drawing, I have used the numeral 10 to designate an operating rod which passes through the longitudinal center of my device. The numeral 11 designates a manually operated knurled handle member permanently secured to the upper end of the rod 10 and the numeral 12 designates a forked tip member rigidly secured to the lower end of the rod 10. Rotatably embracing the rod 10 is a hollow tube 13. This tube 13 has its upper end rotatably mounted in a recess formed in the lower end of the 30 handle member 11 and is held in place at its other end by a plurality of lugs 14 formed on the tip member 12. The numeral 15 designates a ratchet spring having one of its ends permanently secured to the handle member 11 and 35 its other end bent outwardly a slight distance and yieldingly resting against the inside surface of the tube 13. This spring allows the tube 13 and the rod 10 to rotate only in one direction relative to each other. I have used the numeral 40 16 to designate a sleeve having an inside diameter greater than the outside diameter of the tube 13 and of a length less than the length of the tube 13 and rotatably and slidably mounted thereon.

The numeral 17 designates a ratchet spring having one end rigidly secured to the inside of the tube 13 and its other end bent outwardly and extending through a slot 18 cut in the tube 13 to rest against the inside surface of the sleeve 50 16, as shown in Fig. 3 and Fig. 4. This spring 17 is coiled in a direction the same as the direction of coil of the spring 15. By this construction it will be seen that the spring 17 permits the sleeve 16 to be freely turned in one direction, 55

but when an attempt is made to turn the sleeve in the opposite direction the end of this spring will dig into the inside wall of the sleeve and prevent its rotation in that direction. In the drawing I have shown the springs so coiled that the sleeve 16 may be turned to the left and the handle member 11 rotated to the right relative to the tube 13.

The numeral 19 designates an elongated hair-retaining finger hinged at its rear end to the end portion of the sleeve 16 that extends toward the handle member 11, as shown in Fig. 1. This finger 19 is curved transversely to its length in order to conform to the curvature of the circumference of the sleeve 16. The numeral 20 designates a manually operated hair-retaining clamp.

The practical operation of my device is as follows:

The lock of hair to be curled is tied in the usual manner by a string adjacent the scalp. My hair curling instrument is then placed so that the forked member 12 engages the string and is permanently secured thereby to the hair at this point. The lock of hair is then manually wound to the left around the tube 13 a substantial distance for producing a spiral curl. The amount of hair wound around the tube 13, which may be considered the spiral curl form, will naturally be relative to the length of the spiral curl desired. The hair thus far wound around the tube 13 is held for the time being in such condition by the small clamp 20.

Next, the extreme end of the lock of hair is placed under the hair-retaining finger 19 and the sleeve 16 is rotated to the left, thereby successfully winding the end portion of the lock of hair around the sleeve 16 with the extreme ends of the hair being curled first. The hair thus wound on the sleeve 16 when finished will be what is known in the art as a croquignole and its length will be dependent upon the amount of hair wound on the sleeve 16, which may be considered the croquignole curl form. With all of the hair now wound on the instrument the clamp 20 may be removed and the sleeve 16 manually moved away from the handle 11, with the finger 19 and sleeve 16 passing a substantial distance under the hair wound on the tube 13. This action places the croquignole curl tightly against the spiral curl of the lock of hair and by rotating the handle member 11 in an opposite direction to the sleeve 16 or to the right the lock of hair will be stretched tightly around the tube 13 and sleeve 16 in which condition it is ready for treatment by sachet, pad, or like.

From the foregoing, it will readily be seen that the hair wound around the tube 13 will result in a spiral curl and the hair wound about the sleeve 16 which is spiraled at right angles to the longitudinal axis of the center of the spiral curl, will result in what is known in the art as a croquignole. By winding the hair on a single elongated instrument such as I have described and which permits the tightening of the hair from both ends, the hair when its treatment has been completed, has no straight portions, humps, or kinks between the spiral curl and the croquignole curl. My device also permits the hair to be tightly curled near the scalp and may be successfully

operated without change on any length of hair.

With the hair properly and evenly wrapped around my single elongated instrument it may be successfully, uniformly, and evenly contacted by the treating pads, thereby resulting in a hair-dress free from irregularities.

Some changes may be made in the construction and arrangement of my improved combination hair curling instrument without departing from the real spirit and purpose of my invention, and it is my intention to cover by my claims any modified forms of structure or use of mechanical equivalents which may be reasonably included within their scope.

I claim:

1. In a hair curling instrument, a hollow tube, a rod rotatably mounted in said tube, a means for preventing the rotation of said rod in one direction relative to said tube, a sleeve rotatably and slidably mounted on said tube, a means for restriction of rotation of said sleeve in one direction, a means to facilitate the securement of hair to said rod, a means for securement of hair to said tube at times, and a means for securing hair to said second-mentioned tube.

2. In a hair curling instrument, an operating rod having a handle member formed on one end, a means secured to the other end of said rod for facilitating the attachment thereto of a lock of hair, a tube rotatably embracing said operating rod, a means for holding said tube in longitudinal restriction relative to said operating rod, a means for preventing the rotation of said rod in said tube in one direction, and a sleeve rotatably and slidably mounted on said tube.

3. In a hair curling instrument, a tube member, a rod rotatably mounted in and extending through said tube member, a handle member on one end of said rod, a securing element on the other end of said rod, a sleeve member slidably and rotatably mounted on said tube member, and a hair engaging member hingedly secured at one end to said sleeve member.

4. In a hair curling instrument, a tube member, a rod rotatably mounted in said tube member, a ratchet spring for limiting the rotation of said rod to one direction relative to said tube member, a sleeve member rotatably and slidably mounted on said tube member, and a ratchet spring for limiting the rotation of said sleeve member to one direction relative to said tube member.

5. In a hair curling instrument, a tube member, a rod rotatably mounted in said tube member, a ratchet spring for limiting the rotation of said rod to one direction relative to said tube member, a sleeve member rotatably and slidably mounted on said tube member, a ratchet spring for limiting the rotation of said sleeve member to one direction relative to said tube member, a handle portion on one end of said rod, and a forked portion on the other end of said rod.

6. In a hair curling instrument, a tube member, a rod rotatably mounted in and extending through said tube member, a securing element on one end of said rod, a sleeve member slidably and rotatably mounted on said tube member, and a hair engaging member hingedly secured to said sleeve member.

DEWEY E. HARMON. 70
